AUTOMATIC PRINTING TELEGRAPH

Robert Emile Marie Pénot, Paris, France

Application February 10, 1934, Serial No. 710,598
In France February 17, 1933

9 Claims. (Cl. 178—27)

The present invention has for its object to provide a direct mechanical printing device reproducing telegraphic messages in any ordinary characters. This apparatus is such that it enables the automatic translation of the signals corresponding to the characters and the printing of these characters, either on a paper band which is utilized by the operator for the composition of the telegram, or directly on to a page by the use of a cylinder mounted on a carriage and of a special signal used to cause the type to pass from one line to the following line. This new direct printing device is an entirely mechanical apparatus, composed almost entirely of a plurality of identical pieces so as to simplify the manufacture and to facilitate the maintenance of the same.

It comprises essentially a selector, sorting and storing up, in accordance with their reception, the signals corresponding to a character and a printing combining device, receiving the stored up signals from the selector to cause the combining device to come into play in order to print at the moment of printing the corresponding character. The selector and the printing combining device form only a single assembly and operate simultaneously. The apparatus can be adapted for the translation of any code whatsoever, notably recorder signals and five element codes synchronously sent out over the telegraphic systems.

The attached drawings show by way of example and not of limitation one embodiment of the various parts constituting the apparatus, in an adaptation of the invention to the translation of Morse code signals.

35 In the drawings:

Fig. 1 is a perspective view of the parts of the selector.

Fig. 2 is a perspective view of the parts of the printing combining device.

40 Figure 3 shows, on an enlarged scale, a detailed view of a portion of the apparatus.

For the better understanding of the following description it is to be remembered that the Morse code comprises long signals (dashes) and short signals (dots) of which the length, as well as the length of the spacing intervals, are generally adjusted thus: the length of a dot being chosen as a unit period of time, the length of a dash is equal to three units of time, the length of an interval between signs to one unit of time, the length of an interval between letters to three units of time and the length of the interval between words to five units of time.

45 The selector stores up the signals in accordance with their arrival, by the operation of latches controlling the position of turning bars and controls the length of the times of operation by the selection of the signals and the length of the spacing periods in order to release at the appro-

priate moment the printing combining mechanism.

The selector comprises a polarized relay of the balanced type which receives the line currents and which operates an escapement plate. This relay comprises a laminated soft iron armature 1 mounted at its centre on an axis 2 and extended upwardly by an extension 3. The armature 1 is located in the magnetic field formed by preferably laminated pole masses 4 and 5, set up either by a permanent magnet or by a continuous current passing through a suitable winding not shown on the drawings. The pole pieces are, one of north polarity and the other of south polarity and maintain the armature 1 stationary either from one side or the other by the passage of the magnetic flux and also upwardly and downwardly. The armature 1 is moreover subjected to the magnetic field of two bobbins 6 and 7 which receive the line currents. These currents traverse the bobbins sometimes in one direction, sometimes in the other direction, according to whether they correspond to an operative current or to a spacing current. Each inversion of the current in the bobbins 6 and 7 corresponds to an inversion of the direction of the lines of force of the magnetic field in the armature 1 which sets up a change of equilibrium in this armature so that it passes from one pole to the other. In the operative or marking position, the armature 1 is inclined from left to right and in the spacing position it is inclined from right to left. This armature 1, by its extension 3 which is carried thereby, drives an escapement plate 8 which is mounted between two slides which allow it to move horizontally, the displacement being produced by the movements of the armature 1. By a working or marking current received in the bobbins 6 and 7 of the polarized relay, this plate is displaced towards the left and by a spacing current it is displaced towards the right.

On the one hand, plate 8 in its position of working and spacing connects with two toothed wheels 9 and 10 driven by the motor of the apparatus which will be described hereinafter, a 45 working or marking selector (hereinafter termed the "marking selector") and a spacing selector which determine by their displacement the lengths of the signals and spaces. These marking and spacing selectors, which are identical, 50 comprise racks 11 and 12 connected by their pivots 13 and 14 with members 15 and 16 mounted on slides which allow them to move horizontally in the direction of their length, this movement being limited by abutments coming up against 55 their shoulders 17 and 18. Return springs 19 and 20 bring back to their initial position the selectors as soon as the racks 11 or 12 are removed from the toothed wheels 9 or 10 by the displacement of the escapement plate 8 and by a 60

return spring 21. The members 15 and 16 are shaped at one of their ends in the form of asymmetrical cams and can operate by their movement on feelers 22, 23, 24 and 25. As the moment when the armature 1 of the relay is inclined in the marking position the marking selector enters into engagement by its rack 11 with the toothed wheel 9 and is moved in such a manner that for a dash, which is equivalent to 10 three time units of the Morse code, the selector 15 turns the feeler 22 by its cam. For a dash which is too long, the feeler 23 will in its turn be moved by its cam. A dot which is equivalent to 15 a single unit of time will be without effect on the feelers 22 and 23. When the armature 1 of the relay is inclined in the spacing position, the spacing selector enters into engagement by its rack 12, with the toothed wheel 10 and is displaced in such a manner that for a space between letters which is equivalent to three units of time, the selector 16 turns the feeler 25 by its cam. For a space between words, which is equivalent to five units of time, the feeler 24 is operated in its turn. A space between signs which is equivalent to a single unit of time is without effect on the feelers 24 and 25.

On the other hand, this escapement plate 8 controls the movement of a rotary cam 28, hereinafter called the "selection cam", and allows it to make a half turn at the beginning and a half turn at the end of each sign received. To this end the cam 28 as well as the trigger piece 29 is mounted, on a shaft 30 driven by the motor through the intermediary of a friction coupling and is always ready to turn in a clockwise direction, it being retained however at each half turn by the plate 8 which arrests the movement of the trigger 29.

The coupling driving the shaft 30, which is not shown on the drawings with the object of simplifying the same, simply consists of a driven plate connected to shaft 30 mounted between two driving plates. An electric motor is coupled to a main driving shaft 31 which is turned at the rate of one turn for four time units of the Morse code and on which is pinned a pinion 32, which pinion, through the intermediary of a large wheel, not shown on the drawings to simplify the same, drives a pinion connected with the driving plates of the coupling driving the shaft 30 in such a manner that this shaft makes one half turn during the length of a single time unit. The large wheel situated between the main driving shaft 31 and the shaft 30 drives through 55 the intermediary of angle gears and helicoidal gears, friction couplings not shown, mounted on the shafts 33 and 34 of the toothed wheels 9 and 10. These friction couplings are provided with the object of enabling the driving motor to continue to turn when, for a prolonged marking or spacing current, the racks 11 or 12 driven by the toothed wheels 9 or 10 arrive at the end of their movement and are stopped by their abutments which thus have the effect of causing 60 the friction coupling to slip. Also, the friction coupling driving the shaft 30 of the cam 28 slips each time the trigger 29 is stopped in its movement by the plate 8.

In order that the cam 28 and the trigger 29 may be clearly seen on the drawings, the armature 1 of the relay is shown in its marking position and the two members 28 and 29 are shown in the like position. In order to return these members to the spacing position, in which position all the other parts of the apparatus are

shown, the armature 1 of the relay must be inclined to the right which causes the displacement towards the right of the escapement plate 8 as well as the racks 11 and 12. The trigger 29 instead of abutting on the right hand part of the escapement plate would then abut on the left hand part of the same. The projection on the cam 28 instead of being turned upwardly would be turned downwardly.

The selection cam 28 unlatches through the intermediary of the trigger 29 by the escapement plate 8, as hereinbefore described, operates a striker 35 which, for each sign received, unlatches in its turn the latch of the turning bar corresponding to this sign. To this end, the cam 28 operates, during its first half turn, on the passage of the relay and of the plate 8 from the spacing to the marking position, on a lever 36 mounted on a horizontal axis 37, which lever, by its upper part, pushes a pawl 38 pivoted at 39 and, by its lower part, draws a rod 40 pivoted at 41 and, during the second half turn of the cam 28 upon the movement of the relay and of the plate 8 from the marking to the spacing position, the said cam 28 operates the striker 35 by means of an outstanding lever 42 mounted on the horizontal axis 37, operating a bell crank lever 43, pivoted at 44, supporting a rod 45 on which the striker 35 slides, which striker, by reason of its movement from left to right, strikes 46 and unlatches one of the latches 46 mounted on the same rod 47 and kept cocked by the springs 48 mounted on the rods 49.

The latches number thirteen and form six groups of two latches plus a single latch. In order to simplify the drawings, only a single group of latches has been shown. In each group the first is a latch operated by a dot 46a (.), 46b (.), 46c (.), etc. and the second is a latch operated by a dash 46a (-), 46b (-), 46c (-), etc. The thirteenth latch 46g is operated in the case of trouble as will be explained hereinafter. The striker which must be capable of moving in front of the latches and of occupying for this purpose seven successive positions is guided by 45 a vertical slot provided in the rack 50.

This rack, supported by two horizontal slides, is moved tooth by tooth, by the pawl 38 controlled by the cam 28, at each of its movements from spacing to marking and is maintained in its successive positions by a retaining pawl 51 pivoted on a shaft 52 from which it is independent. A spring 53 sets the pawls 38 and 51 and a spring 54 returns the rack to its initial position, with one tooth of the rack in advance of the first group of latches as soon as the combination having been registered by the combining device, as will hereinafter be explained, a lever 55 controlled through the shaft 52 by the lever 56 has disengaged the pawls 38 and 51 from the rack. At each of its seven positions the striker can operate either a dot latch or a dash latch. It follows for this purpose a horizontal groove which is provided in a guide 57 in the form of a T, the lower part of which is pivoted at 58 on a controlling member 59 called the switching arm, which is mounted on an axle 60, and, at each new sign, is placed in a position enabling the striker to register a dot, by the rod 40 operated at each first half turn of the cam 28.

When the sign received is a dot, the striker 35 unlatches on the second half turn of the cam 28 the dot latch of the group corresponding to the sign received before which it has

been positioned by the rack 50, the first group, if it should be the first sign, the second group if it should be second sign etc. such the above

140
springs 94 mounted on the rods 95. These turning bars at the moment of their movement towards the right, produced by the thrust of the cam 75 on the levers 85 and 90 which control them are some in the spacing position and others in the marking position according to whether the latch which is affected by them has been or has not been unlatched by the striker 35 at the moment of the selection of the signals forming the combination which they are about to transmit to the combining device. 10
13. Thirteen com-

transmit to the combining device. The combining device comprises thirteen combining discs 96a (.), 96a (-), 96b (.), 96b (-) . . . 96g, mounted side by side on the same horizontal axis which can take up by an angular displacement which makes them each turn a little in one direction or the other, the position, marking or spacing, which the thirteen turning bars 93 give to them. Each one of the thirteen combining discs is operated by the turning bar which corresponds to it through the intermediary of pivoting pieces 97, all identical and mounted on the same axis 98 which are moved by their turning bars 93 either at their lower part or at their upper part according to whether the turning bars are in the spacing position or the marking position and they remain in the same position until, for a new combination, the turning bars again operate them. Of the thirteen discs which form the combining device, the first twelve correspond

the combining device, the first twelve correspond to the first twelve latches 46 and comprise two by two the six groups necessary to form the combinations of the characters according to the Morse code in question. In each of the six groups the first disc corresponds to and comes into operation for a dot sign, the second disc corresponds to and comes into operation for a dash sign. The function of the thirteenth disc will be explained hereinafter. 35

hereinafter. As soon as, by this operation, the combining device has registered the combination received, the selector is returned to its initial position in order to be ready to sort and store up the following signals. To this end, a return spring 99 brings back the thirteen turning bars by returning to their original position the levers 85 and 90 as soon as the projection of the cam 75 has passed under the roller 83. An instant later, the projection of this cam 75 operates on the roller 82 of the lever 80 carrying at its extremity a resetting projection 100 which presses on the thirteen turning bars in such manner as to reset the latches used during the storing up of the preceding signals. The lever 85, mounted on axis 86, is connected to a lever 101 which is perpendicular to it and which by a connecting link 102, pivoted at its extremity at 103, operates the lever 56 to which it is fixed by a pin 104 in order to disengage the pawls 38 and 51 which allow the rack 50 to return to its original position as hereinbefore described.

inbefore described. From this moment the selector is ready to sort and store up the signals forming a new combination which can arrive. During the selection and storing up of these new signals the cam shaft continues its rotation in order to print the character corresponding to the combination transmitted by the selector to the combining device. To this end, each combining disc is slotted on its periphery in a different fashion for each one so as to form for each combination of the code a longitudinal slot in the whole series of thirteen discs which will permit a type bar 105 to engage therewith. The discs of the combining device are surrounded by fifty one type bars which are 75

all identical and correspond to the characters of the code. Each type bar at one extremity gears with a character carrying lever 106 capable of pivoting on an axis 107 and maintained in engagement with it by a spacing piece not shown on the drawings. The fifty one character carrying levers 106 are identical and support the typographical characters 108 which are terminated by a slightly conical part engaging in a like conical part at the end of the levers 106 and are turned each according to the position which it occupies in such a manner as to strike normally on a cylinder 117 on which the typing point is situated on the main axis of the whole printing combining device assembly. Suitable combs guide the type bars and the character carrying levers. At the other extremity of each type bar is hooked a spring 109 which tends at all times to return the character carrying lever against its type bar and to press the type bar 105 against the discs 96 of the combining device. A type disc 110 which maintains in its initial position all the type bars 105 clear of the discs 96 of the combining device, slides along the main axis of the combining device by means of a lever 111 mounted on a pivot 112 which is connected to it by a pin 113 and which is unlatched by a type spring 114 under the control of a roller 115 mounted at 116 which follows the face of the cam 76.

At the beginning of the rotation of the cam 76 the type disc 110 does not move in order that the turning bars 93 may transmit the stored up combination to the discs 96 of the combining device. As soon as the combining device has received the combination the type disc 110, due to the shape of the cam 76, is moved by the spring 114 and the fifty one type bars fall against the combining device. Only that type bar corresponding to the set up combination encountering the longitudinal slot formed by the thirteen discs hooks itself on to the type disc; the other fifty pushed on the combining discs are not caught up by this type disc. At this moment the cam 76 presents a hollow under the roller 115 and the pull of the spring produces a movement of the type bar hooked on to the disc 110 which projects the corresponding type character against a band of paper passing over the roller 117 which produces the impression of the character. During the last part of its turn the cam 76 returns the type disc to its initial position in order to move the type bars away from the combining device and to retighten the spring 114. The spring 109 of the type bar which comes into play also returns its character carrying lever to its initial position against this type bar. An adjustable abutment 118 enables, by limiting the movement of the type disc 110, the typing to be regulated at will, this being due solely to the tension of the spring 114 and is independent of the speed of the cam shaft 73 and hence of the speed of reception. Inking is assured by means of an inked ribbon passing before the band of paper and which is, as in writing machines, supported by appropriate spools.

The thirteenth disc 96g of the combining device, which has already been referred to, corresponds to the thirteenth latch 46g which has also been mentioned, and functions in the case of trouble, to prevent the typing of an erroneous character, by blocking all the slots which might have been formed in the first twelve discs and by forming a slot in which there engages at the moment of the impression a type bar controlling the typing 75 of the signal "not understood". To this end the

latch 46g which controls the disc 96g of the combining device is unlatched in either of two ways, either by striker 35 in the case of the lack of a space between groups of signs due to parasites coming between two or three groups of signs and forming with the signs a combination comprising at least seven signs, the maximum number of signs provided by the Morse code being six; or by the feeler 23 which is turned by the cam of the marking selector 15 in the case of presence of a dash which is too long due to a blocking parasite between several signals through intermediary of connecting links and levers, not shown on the drawings, which have the effect of unlatching the latch 46g in the same manner as the striker 35.

The printing cylinder 117 which drives the paper band on which the type is produced is mounted on an axle 119 and is connected to a ratchet wheel 120 driven by a pawl 121 set by a spring 122 and maintained in each of its new positions by a spring 123 disposed below a diameter passing through the point of the pawl 121 so as to prevent overthrow which always gives rise to irregular spacing. The pawl 121 is mounted on an axle 124 on a lever 125 connected to a shaft 126 on which is also fixed the control lever 127. A spring 128 tends constantly to drive the pawl 121 and to cause it to turn the printing roller 117 but an abutment 129 limits the movement of the control lever 127. This abutment 129 is a cylindrical member traversed by a pusher 130 forming towards the front an extension on which presses the control lever 127 and which possesses at its periphery a shoulder against which a spring 131 pushes. A latch 132 on which the other side of the shoulder presses keeps this abutment in such a position that the pawl 121 can at each operation only drive the ratchet wheel 120 one tooth. At the moment of typing through the intermediary of a return lever 133 mounted on an axle 134 operated by an arm of the lever 111 and of an adjustable pusher 135 pivoted thereon at 136, the pusher 130 acts on the control lever 127 and sets the pawl 121 which drives the ratchet wheel 120 one tooth as soon as the impression of the character has taken place. This advance of the paper band produced tooth by tooth on the ratchet wheel 120 by the pawl 121 corresponds to the spacing of two consecutive characters. On the selection, by the spacing selector 16, of an interval between words, the feeler 24 turned by the cam of this selector 16 frees the abutment 129 by disengagement of the latch 132, through the intermediary of the shaft 137 and a lever 138 on which is pivoted at 139 the latch 132 in order to prepare for a double advance of the paper band following upon the displacement by the spring 131 of the abutment 129. This double advance will be produced at the moment when, after the impression, the pawl 121 engages with the ratchet wheel 120. At the following impression the pusher 135 will again set the latch 132 of the abutment 129 and at the same time it will reset the pawl 121. The shaft 126 also operates the advancing pawls of the inked ribbon and its direction changing device by suitable means similar to those already known in writing machines.

The direct mechanical printing device reproducing telegraphic messages in ordinary characters thus constructed will only require of the operator a simple suitable adjustment of the speed of rotation of the driving electric motor which speed must be adjusted in accordance with the speed of the signals to be transcribed. A

rheostat will enable the speed of the motor to be regulated and a scale graduated in words per minute, mounted on the motor, renders this adjustment particularly easy.

5 In the preceding description the rack 50 must return to its initial position in a very short time which corresponds to the time between the selection of an interval and the beginning of the following sign, which can present considerable disadvantages at a high speed.

10 In order to overcome this state of affairs, the modification shown in Figure 3 may be employed. Fig. 3 shows, on an enlarged scale, a detailed view of the improved mechanism by means of which 15 the pawls 38 and 51 are disengaged from the rack 50.

15 There is thus obtained, as will hereinafter be explained, a much longer time within which the rack 50 can return to its initial position.

20 For the sake of clearness, the pawls 38 and 51 have not been shown completely in Figure 3, but only the points 38a and 51a which press on the lever 55.

25 In the modification in question, the rack 50, instead of coming to rest in a position in which one tooth of the same is in advance of its first marking or working position, returns actually to its first marking or working position, which is its position of rest, so that for the first sign it 30 is not displaced, which provides for the return of the rack to its position of rest, in addition to the time between the selection of an interval and the beginning of the following sign, all the time of the passage of this sign, together with a part of 35 the interval which follows this sign. To this effect, a pawl 140 pivoted at 141 and controlled by a spring 142 (Figure 3) maintains the lever 55 in the upper position through the medium of a notch 55a provided on this member, this being 40 the position in which the rack 50 is disengaged from its pawls 38 and 51, as soon as the cam shaft has operated it due to an interval between words. The rack 50, disengaged from the pawls 51 and 38, returns to its first working position which is 45 its position of rest and is all ready for the first sign.

On the arrival of this first sign, the pawl 38 is operated without displacing the rack since it is disengaged therefrom.

50 In its displacement this pawl 38 pushes by its forward end 38a (Fig. 3) the pawl 140 which by reason of this movement frees the lever 55 and allows the pawl 38 and 51 to fall on to the rack.

The second sign will then displace this rack 55 50 by one tooth and the above described operation will take place.

The control of the lever 55 is in this case effected by a simple pusher (not shown) in such a manner as not to interfere due to its engagement 60 therewith with the return of the levers 101 and 85.

What I claim is:—

1. A direct mechanical printing apparatus reproducing telegraphic messages in ordinary characters, comprising a selector mechanism capable of sorting and storing the received signals corresponding to each character intended to be printed, including a polarized relay provided with an oscillating armature having an escapement plate secured thereto, the relay being excited by incoming signal currents and operating said armature, a main driven shaft, a pair of toothed wheels continuously driven from said main shaft, two pivoted racks individually adjacent to said 75 toothed wheel and capable of approximately lon-

gitudinal movement together with their pivotal mountings and also capable of movement about said pivotal mountings into angular positions controlled by said escapement plate, said escapement plate being capable upon movement 5 thereof by oscillation of said armature, of causing alternatively one of said racks to engage with the respectively adjacent toothed wheel and be longitudinally moved by said wheel for the duration of the engagement of the rack with the 10 wheel, a movable selector cam controlled in movement by said escapement plate, and a printing combining device capable of receiving the stored signals from said selector mechanism and operating to print the corresponding character 15 and controlled in operation by said selector cam and said racks, there being means for driving said main shaft.

2. A direct mechanical printing apparatus reproducing telegraphic messages in ordinary 20 characters, comprising a selector mechanism capable of sorting and storing the received signals corresponding to each character intended to be printed, a printing combining device capable of receiving the stored signals from said selector 25 mechanism and operating to print the corresponding character at a predetermined correct moment and forming a unitary assembly with said selector mechanism, a driven rotatable main shaft for said unitary assembly, the selector 30 mechanism comprising a polarized relay excited by the line currents of the incoming messages, two slides, an armature operated by said relay and provided with an escapement plate which is secured to said armature and disposed between 35 said two slides, two racks connected to said slides, the slides being individually slidable with respect to said escapement plate, a pair of toothed wheels engaged alternately by said racks so as to be capable of driving the respective rack engaging 40 one of said wheels upon movement of said escapement plate, a longitudinally movable member connected to each rack and mounted between a pair of feelers and capable of moving one or both feelers upon being moved by the corresponding rack, a plurality of latches, a striker capable of unlatching said latches in succession, a selector cam controlling said striker and being 45 itself controlled in movement by said escapement plate, and turning bars controlling operation of the printing combining device and individually associated with and controlled by said latches.

3. A direct mechanical printing apparatus reproducing telegraphic messages in ordinary 55 characters, comprising a selector mechanism capable of sorting and storing the received signals corresponding to each character intended to be printed, a printing combining device capable of receiving the stored signals from said selector 60 mechanism and operating to print the corresponding character at a predetermined correct moment and forming a unitary assembly with said selector mechanism, a driven rotatable main shaft for said unitary assembly, the selector 65 mechanism comprising a polarized relay excited by the line currents of the incoming messages, two slides, an armature operated by said relay and provided with an escapement plate which is secured to said armature and disposed between said 70 two slides, two racks connected to said slides, the slides being individually slidable with respect to said escapement plate, a pair of toothed wheels engaged alternately by said racks so as to be capable of driving the respective rack engaging one 75

of said wheels upon movement of said escapement plate, a longitudinally movable member connected to each rack and mounted between a pair of feelers and capable of moving one or both feelers upon being moved by the corresponding rack, a plurality of latches, a striker capable of unlatching said latches in succession, a selector cam controlling said striker and being itself controlled in movement by said escapement plate, and turning bars controlling operation of the printing combining device and individually associated with and controlled by said latches, while the printing combining device comprises a plurality of discs mounted side by said so as to move upon a common axis corresponding to said turning bars, each disc corresponding to one of the turning bars and being peripherally slotted in different manner than the other discs and angularly displaceable in either one or another direction by the same in order to assume a marking or spacing position, respectively, so as to form for each combination of the code a longitudinal slot in the whole series of said discs, and a plurality of similar striking bars surrounding said discs and individually engaging with a printing type lever and capable of engaging in said longitudinal slot when formed adjacent to the same and by longitudinal displacement operating said type lever and causing it to print the character thereon when the selector mechanism causes operation of said striking bars.

4. A direct mechanical printing apparatus reproducing telegraphic messages in ordinary character, comprising a selector mechanism, including a polarized relay excited by the line currents of the incoming messages and operating an armature having an escapement plate which is secured thereto and disposed between two slides, two racks connected to said slides, a pair of toothed wheels engaged alternately by said racks so as to be capable of driving the respective rack engaging one of said wheels upon movement of said escapement plate, a longitudinally movable member connected to each rack and mounted between a pair of feelers and capable of moving one or both feelers upon being moved by the corresponding rack, a plurality of latches, a striker capable of unlatching said latches in succession, a selector cam controlling said striker and being itself controlled in movement by said escapement plate, and turning bars controlling operation of the printing combining device and individually associated with and controlled by said latches, a printing combining device comprising a plurality of discs mounted side by side so as to move upon a common axis corresponding to said turning bars, each disc corresponding to one of the turning bars and being peripherally slotted in different manner than the other discs and angularly displaceable in either one or another direction by the same in order to assume a marking or spacing position, respectively, so as to form for each combination of the code a longitudinal slot in the whole series of said discs, there being driving means for said apparatus, and a plurality of similar striking bars surrounding said discs and individually engaging with a printing type lever and capable of engaging in said longitudinal slot when formed adjacent to the same and by longitudinal displacement operating said type lever and causing it to print the character thereon

when the selector mechanism causes operation of said striking bars, the turning bars being thirteen in number and likewise the discs being thirteen in number, twelve of the latter bars and discs serving to select the appropriate character, and the thirteenth bar and disc serving to indicate error in the signals.

5. Printing telegraph signal translating apparatus comprising, in combination, there being driving means, a pair of longitudinally displaceable members, mechanism transforming the incoming signal currents into displacements of said displaceable members, which in the case of one of said members is proportional to the duration of the signals and in the case of the other proportional to the duration of the intervals between the signals, a plurality of angularly displaceable and juxtaposed discs peripherally slotted in individually different manner, a plurality of turning bars individually controlling said discs and capable of causing the same to assume positions corresponding to the typographic characters, means operated by said driving means and said longitudinally displaceable members effective to turn said turning bars according to the successive incoming signals constituting each given typographic character, printing instrumentalities driven by said driving means having individual characters borne upon distinct levers, and engaging means operating solely one character lever to type the character thereon corresponding to the positions assumed by said discs, which engaging means engage the slots in the peripheries of said discs to individually operate the appropriate character lever for each combination of said slots.

6. Printing telegraph signal translating apparatus according to claim 5, wherein each of the longitudinally displaceable members comprise a rack engaging a toothed wheel, one of the racks serving to determine the length of the signal by the extent of its movement and the other rack serving similarly to determine the length of the interval between the signals.

7. Printing telegraph signal translating apparatus according to claim 5, wherein the engaging means comprise articulated levers which are capable of individually seating in the individual slots in the peripheries of the discs when aligned to correspond to the character on the character levers operated by said articulated levers.

8. A printing telegraphic signal translating apparatus according to claim 5, wherein the character levers print the characters on a paper band passed over a platen provided with means for advancing the platen after each operation of the printing instrumentalities including the printing of each character.

9. A printing telegraphic signal translating apparatus according to claim 4, wherein the striker is capable of assuming a multiplicity of positions distributed over two parallel lines corresponding, respectively, to one type of signal such as dots and to another type of signal such as dashes, and means for displacing said striker transversely to said lines toward the line corresponding to the type of signal being received and shifting said striker to a position parallel to said lines during the interval between signals.
